(57) **CLAIM**

The ornamental design for a cable gland, as shown and described.

DESCRIPTION

FIG. 1 is a top perspective view of a cable gland;
FIG. 2 a bottom perspective view of the cable gland;
FIG. 3 is a top view of the cable gland;
FIG. 4 is a bottom view of the cable gland;
FIG. 5 is a front view of the cable gland;
FIG. 6 is a rear view of the cable gland; and,
FIG. 7 is a side view of the cable gland.

The broken line showing of the cable gland represents unclaimed subject matter and forms no part of the claimed design.
